CHARGING DEVICE

Herbert W. Kelly, Chicago, Ill., assignor to
Mechanite Metal Corporation

Application December 14, 1944, Serial No. 568,168

3 Claims. (Cl. 266—27)

My invention relates to apparatus for conveying material and more particularly to apparatus for charging metallurgical furnaces, cupolas, and the like.

The present description will be given in connection with the operation of charging a cupola for the melting of iron or other materials, although the invention is to be understood as also being directed to charging of other metallurgical furnaces and similar devices for processing metal, and to other conveying of material.

In the operation of a cupola, it is usual to charge the cupola with pig iron, iron or steel scrap, coke, fluxing material and such other material as may be desired. The different materials are positioned in appropriate layers in the bottom of the cupola to form the desired bed. Upon combustion of coke and the melting of the metal, the layers of material progressively sink down in the shaft of the cupola. The melted iron and fluid slag are periodically drawn off in the usual manner. It is necessary to periodically recharge the cupola with additional material as the melting and the drawing off operation continue.

The apparatus as described may be used to carry a magnetic drop, or cone bottom bucket or any other suitable receptacle, and therefore, is illustrated in the drawings in its simple outline form.

An object of my invention is the provision of improved apparatus and method for conveying material from one location to another.

Another object of my invention is the provision of improved apparatus to automatically engage a charging vessel, lift same to the charging door of a metallurgical furnace and place it in position to discharge its contents, and thereafter return the vessel to its original position and disengage therefrom.

Another object of my invention is the provision of improved guide means to automatically guide a metallurgical furnace charging apparatus.

Another object of my invention is the provision of a worm screw shaft to raise the charging boom of a metallurgical furnace charging apparatus.

Other objects and a fuller understanding of my invention may be had by referring to the following description and claims, taken in conjunction with the accompanying drawings, in which:

Fig. 1 is a side elevational of a cupola and my improved charging apparatus;

Figure 2 is a view along the lines 2—2 of Figure 1 and illustrates an interior view of the

cupola, and a top view of the charging apparatus with the motor and gear reduction unit thereon;

The Figure 3 is a sectional view along the lines 3—3 of Figure 1 with a full top view of the charging boom as it appears when in contact with the guide means just below the line 3—3;

Figure 4 is a cross-sectional view of the charging apparatus frame along the lines 4—4 of Figure 1 and illustrates a full top view of the charging boom as it appears just below the line 4—4, and in full engagement with the charging bucket; and

Figure 5 is a cross-sectional view of the charging apparatus frame along the lines 5—5 of Figure 1 and illustrates the position of the curved section of the guide member of the frame at this point, with the charging boom in contact therewith and spaced from the charging bucket.

With reference to the Figure 1, I illustrate a cupola 10 having a charging door 12 in the upper portions thereof and a charging apparatus illustrated generally by the reference 11 which is used to carry a charging bucket 13 from a loading floor or conveyor 14, place it within the cupola 10 at the charging door 12, and return it to the loading floor 14.

The charging apparatus 11, may embody many specific structural designs employing the same principle, and is illustrated comprising a worm screw shaft 15 which is rotated about its longitudinal axis by means of a motor 17 geared thereto by means of a gear box 16. A boom 18 is carried by the shaft 15 and is connected thereto by an internally threaded member 19. The member 19 is illustrated as one continuous member, but may be divided into two or more individual members if so desired.

The boom 18, which carries the bucket 13, is guided in its upward and downward path by means of a guide post 20 for the upward path, and a guide post 21 for the downward path. The guide post 20 is provided with a curved section at its uppermost part which is illustrated generally by the reference character 22. This guiding section is curved to permit the boom to rotate relative to the cupola and position the bucket 13 within the charging door 12 of the cupola. The guide post 21 is similarly curved at its lower end and this curved section is illustrated generally by the reference character 23. The curved section 23 is provided to swing the boom 18 into or out of engagement with the bucket 13 according to whether the boom is ascending or descending.

Although the guide posts 20 and 21, or their equivalent, are all that is necessary theoretically

for the operation of my improved charging apparatus, structural requirements depend upon additional support. Therefore, two additional support posts are illustrated by the reference characters 24 and 25, in the Figures 2 to 5. Other suitable support is provided by the tie bar 26 extending from the charging apparatus 11 to the cupola 10, and any suitable interconnecting support members such as the members 27.

Although it may be desirable in some instances to maintain the bucket 13 continuously in the support of the boom 18, it is often desirable to provide a number of charging buckets 13 which may be loaded at leisure and moved to the charging apparatus 11 to be emptied within the cupola 10. Therefore, it is understood that the curved section 23 of the guide post 21 is optional, although desirable.

In the operation of my improved apparatus, it will readily be understood that friction between the interlocking thread means 19 and the worm screw shaft 15 will cause the boom 18 to rotate about the shaft 15 unless the boom is held from rotation by external means. Therefore, with the bucket 13 and the boom 18 in the position illustrated in the Figure 5, if the shaft 15 is caused to rotate in a counterclockwise direction as viewed axially from the top thereof, the boom 18 will rotate about the shaft 15 and come into contact with the bucket 13 as illustrated in the Figure 4. The resistance offered by friction between the loaded bucket 13 and the loading floor or conveyor 14 is great enough to stop the rotation of the boom 18, whereupon relative movement is started between the teeth or threads of the shaft 15 and the interlocking thread means 19. The boom 18 then begins to ascend axially upward along the shaft 15 until the bucket 13 is lifted clear of the floor 14. When the bucket 13 is lifted clear of the floor 14, the boom 18 is again free to rotate counterclockwise about the longitudinal axis of the shaft 15. Therefore, the guide post 20 is positioned to interfere with the rotation of the boom 18 and hold it at a distance from the cupola 10. Thereafter, the boom 18 is held in firm contact with the guide post 20 by the aforescribed screw thread friction. The boom 18 with the bucket 13 thereon then moves progressively upwardly with the boom 18 positioned any desirable distance away from the cupola 10 until the vicinity of the charging door 12 is reached. The Figure 3 illustrates the appearance of the boom 18 in its ascent to the charging door 12. Upon reaching the area 22 of the guide post 20, the boom 18 is permitted to rotate further in a counterclockwise direction and thereby swings the bucket 13 into the interior of the cupola 10 through the charging door 12. This position of the bucket and boom is best illustrated in the Figure 2. At this point the contents of the bucket 13 are emptied into the cupola 10.

To return the bucket 13 to its original position and release it from the boom 18, the shaft 15 is reversed in its rotational direction and is caused to rotate clockwise. The clockwise rotation, because of the aforescribed screw thread friction, tends to rotate the boom 18 in a clockwise direction and withdraw the bucket 13 from the charging door 12. However, the boom 18 is in direct contact with the curved section 22 of the guide post 20 and this curved section also tends to withdraw the boom 18 and the bucket 13 from the interior of the cupola 10. This described clockwise rotation of the boom 18 continues until the

boom 18 is in contact with the guide post 21 whereafter relative movement is caused between the shaft 15 and the interlocking thread member 19 and the boom moves axially downwardly relative to the shaft 15. Again, the boom 18 is held in firm contact with the guide post 21 as long as the shaft 15 is rotating in a clockwise direction. The guide post 21 is so formed and positioned, that the boom 18 will place the bucket 13 down upon the identical spot from which it was picked up. This position is again illustrated in the Figure 4. Thereafter, the shaft 15 continues to rotate in a clockwise direction, and the boom 18 begins to descend relative to the bucket 13. At this point, the boom 18 is allowed to rotate further because of the curved guide section 23 of the guide post 21. This further rotation is continued until the boom 18 swings free of the bucket 13.

The loading floor or conveyor 14 may be so arranged that the empty bucket 13 may be easily moved out of position, and a filled bucket moved in to take its place. The process as described is then repeated again with the new charging bucket.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In a charging apparatus for a metallurgical furnace having a charging door in an upper portion thereof through which a bucket of material is moved, the improvement of carrying means for carrying said bucket from a loading floor, through the said charging door into the interior of the furnace and return, said improvement comprising a substantially vertical worm screw shaft adapted to be rotated about its longitudinal axis, power means to rotate the shaft, a horizontally disposed boom adapted to carry said bucket, interlocking threads on said boom to engage said shaft, and guide means to guide said boom and bucket through predetermined arcs of rotation during the carrying period, whereby the power means may rotate the shaft and cause the boom to lift the bucket and position same in the furnace to discharge its contents, and return.

2. In a charging apparatus for a metallurgical furnace having a charging door in an upper portion thereof through which a bucket of material is moved, the improvement of carrying means for carrying said bucket from a loading floor, through the said charging door into the interior of the furnace and return, said improvement comprising a substantially vertical worm screw shaft adapted to be rotated about its longitudinal axis, power means to rotate the shaft, a horizontally disposed boom adapted to carry said bucket, interlocking threads on said boom to engage said shaft, and guide means to guide said boom and bucket through predetermined arcs of rotation during the carrying period, screw thread friction between said boom interlocking threads and said shaft tending to impart a rotary movement to said boom in the direction of rotation of said shaft, said guide means limiting the rotary movement of said boom, said interlocking threads causing the boom to move axially relative to said shaft when the shaft is rotated, and said guide means guiding said boom in radial position respective to said shaft.

3. A horizontally disposed boom elevatable and rotatable about a worm screw shaft, said worm screw shaft operatively connected with said boom and tending to swing same horizontally about the shaft and to elevate it, guide means to limit the said swinging and guide the boom relative to said shaft, said guide comprising at least two posts extending generally parallel to said screw and lo-

5 cated to arrest the swinging of said boom, curved longitudinal sections on said posts, said swing tendency holding said boom in contact with said guide means, whereby said boom is guided into different radial positions relative said screw by virtue of the curved guide sections as the boom is elevated relative to the said screw.

HERBERT W. KELLY.
